CLAIM

The ornamental design for a digital reader for immunoassay test device, as shown and described.

DESCRIPTION

FIG. 1 is a front view of a digital reader for immunoassay test device according to the present design;

FIG. 2 is a back view of the digital reader for immunoassay test device of FIG. 1;

FIG. 3 is a top view of the digital reader for immunoassay test device of FIG. 1;

FIG. 4 is a bottom view of the digital reader for immunoassay test device of FIG. 1;

FIG. 5 is a right view of the digital reader for immunoassay test device of FIG. 1;

FIG. 6 is a left view of the digital reader for immunoassay test device of FIG. 1; and,

FIG. 7 is a perspective view of the digital reader for immunoassay test device of FIG. 1.
